(57) **CLAIM**

The ornamental design for a ball lamp as shown and described.

DESCRIPTION

FIG. 1 is a front, right and top perspective view of a first embodiment of a ball lamp, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the first embodiment of the ball lamp in a position of use.

FIG. 10 is a front perspective view of the first embodiment of the ball lamp in another position of use.

FIG. 11 is a front, right and top perspective view of a second embodiment of a ball lamp.

FIG. 12 is a rear, left and bottom perspective view thereof.

FIG. 13 is a front elevation view thereof.

FIG. 14 is a rear elevation view thereof.

FIG. 15 is a left side elevation view thereof.

FIG. 16 is a right side elevation view thereof.

FIG. 17 is a top plan elevation view thereof.

FIG. 18 is a bottom plan elevation view thereof.

FIG. 19 is another front, right and top perspective view of the second embodiment of the ball lamp in a position of use.

FIG. 20 is an exploded elevation view of FIG. 12.

FIG. 21 is a front perspective view of the second embodiment of the ball lamp in another position of use.

FIG. 22 is a front, right and top perspective view of a third embodiment of a ball lamp.

FIG. 23 is a rear, left and bottom perspective view thereof.

FIG. 24 is a front elevation view thereof.

FIG. 25 is a rear elevation view thereof.

FIG. 26 is a left side elevation view thereof.

FIG. 27 is a right side elevation view thereof.

FIG. 28 is a top plan elevation view thereof.

(Continued)

FIG. 29 is a bottom plan elevation view thereof. FIG. 30 is another front, right and top perspective view of the third embodiment of the ball lamp in a position of use. FIG. 31 is an exploded elevation view of FIG. 23; and, FIG. 32 is a front perspective view of the third embodiment of the ball lamp in another position of use. The broken lines depict portions of the ball lamp that form no part of the claimed design. The additional broken lines in FIGS. 9, 10, 19, 21, 30, and 32 represent environment and form no part of the claim.
